U.S. Appl. No. 29/944,681, filed May 29, 2024, Peacock.

Primary Examiner — Omeed Agilee

(74) Attorney, Agent, or Firm — Polsinelli PC

(57) **CLAIM**

The ornamental design for a bottle, as shown and described.

DESCRIPTION

FIG. 1 is a top perspective view of a bottle.

FIG. 2 is a bottom perspective view of the bottle.

FIG. 3 is a front view of the bottle.

FIG. 4 is a back view of the bottle.

FIG. 5 is a side view of the bottle.

FIG. 6 is an opposite side view of the bottle.

FIG. 7 is a top view of the bottle; and,

FIG. 8 is a bottom view of the bottle.

The broken lines in the drawings illustrate portions of the bottle and form no part of the claimed design.

1 Claim, 8 Drawing Sheets(56)
